BALLAST FOR AIRCRAFT

Application filed April 17, 1930. Serial No. 444,937.

This invention relates to ballast for aircraft and has for an object to provide improved means for storing and discharging liquid ballast, generally water.

5 A further object of the invention is to provide, in an aircraft, a plurality of ballast compartments which may be discharged, as occasion requires, and making provision for discharging a pre-determined portion of the ballast therefrom simultaneously.

10 A further object of the invention is to provide, in an aircraft, a plurality of containers for liquid ballast, with a conduit for discharging and with manually operated valves controlling the flow of ballast from the containers to the conduit, which are operable to discharge a pre-determined portion of the ballast content.

15 A further object of the invention is to provide, in an aircraft, a plurality of ballast compartments, a conduit for discharging ballast from the containers, with valves interposed, and means located convenient to the pilot, or operator of the craft, for controlling the 20 valves.

25 The invention therefore comprises an aircraft having a plurality of independent ballast containers with a conduit associated with said containers and adapted to discharge the ballast in the form of a spray with means under the control of the pilot for discharging, from said containers, into said conduit a pre-determined portion of the ballast content.

30 My invention is directed to other objects and possesses other features of novelty and advantage, some of which, together with the foregoing, will be hereinafter set forth.

In the drawings:

35 Figure 1 is a view partly in side elevation partly in section, of a conventional car, forming a part of an aircraft, showing in sections the location and relation of ballast compartments and the operating means.

40 Figure 2 is a view taken on the same plane as Figure 1, but on an enlarged scale,

45 Figure 3 is a view, partly in diametrical section and partly in elevation, of one of the valves controlling the discharge of ballast from the container,

50 Figure 4 is a transverse sectional view

through the valve and valve organization taken on line 4—4 of Figure 3, and showing line 3—3 as the plane of Figure 3, and

55 Figure 5 is a transverse sectional view through the valve taken on line 5—5 of Figure 3.

Like characters of reference indicate corresponding parts throughout the several views.

60 As shown in the drawings, merely for the purpose of illustration and without limitation, a buoyant chamber 10 is indicated, with a car 11 suspended therebeneath in the usual manner, said car being shown merely as illustrative.

65 At some position within the car, preferably beneath the floor 12, will be located a plurality of ballast tanks 13. As shown at Figures 1 and 2, these ballast tanks 13 are alternated by tanks 14 intended to carry fuel, but it is to be understood of course, that the interposition of these tanks 14, or their very existence, is not a part of the present invention and that they in no way effect the invention so far as it relates to the ballast tanks. All of the tanks are shown with filler nipples 15, but 70 again this is merely illustrative and the tanks, both of the type shown at 13 and those shown at 14, may be filled in any manner and by the use of any appliances or accessories.

75 Located below the plane of the several tanks, a conduit 16 is employed, which will preferably extend throughout the entire length occupied by the said tanks, and will terminate at some convenient point without the car in means, as the sprinkler head 17 80 shown at Figure 1, for diffusing, to a certain extent, the ballast which will be discharged therefrom in the manner hereinafter more fully disclosed.

85 In the type of aircraft upon which such ballast is usually employed, an internal combustion engine furnishes the power, such power plant being illustrated conventionally at 18, with an exhaust manifold 19 leading to an exhaust pipe 20 with a by-pass 21, controlled by a valve 22, leading to the conduit 16 so that, as elected by the operator, the exhaust may be deflected, from the regular exhaust pipe 20, into the branch 21 and through 90 95 190

the conduit 16 to further diffuse the ballast discharged from the spray head 17.

Beneath each of the containers 13 a valve 23 is located, in an appropriate housing 24. A section of pipe 25 runs from the housing 24 upwardly into the tank to a position adjacent the top of the tank, ratio of the length of pipe to the height of the tank being predetermined. As shown in the drawings, the 10 length of the pipe to the height of the tank is as 4 to 5, but such length is wholly elective and may be varied as circumstances or choice may dictate. This pipe 25 is in position to register with an opening 26 formed in the 15 valve 23. At Figure 4 a transverse section of the valve is shown, showing the form of this opening 26. When the valve 23 is revolutionally moved in the direction of the arrow, the opening 26 will form communication between the pipe 25 and the nipple 27, interposed between the housing 24 and the conduit 16, so that the contents of the containers above the ends of the pipes 25 will be discharged through said pipe, through the 20 openings 26 and into the conduit 16.

A second pipe 28 forms communication also between the container 13 and the valve housing 24, such communication being at the bottom of the container and in position to 30 register with the opening 29 in the valve 23 when the valve 23 shall be further rotated in the direction of the arrow. This opening 29 communicates with a passage 30 extending longitudinally of the valve 23 and communicating with the opening 26. The extent of the opening 26 is such that when the opening 29 is brought into registry with the pipe 28, the opening 26 will still be in communication with the nipple 27 so that the ballast 35 will flow through the pipe 27, opening 29, passage 30, opening 26, nipple 27 into said conduit. Means, as the screw cap 31, is provided for maintaining the valve 23 properly seated within the housing and means for rotating the valve is provided, conventionally 40 shown as a pulley 32. Each of the several valves are interconnected by belts or bands 33 passing over and about the several pulleys 32. Within some part of the car, as for 45 instance, the compartment 34, which may for convenience be termed the pilot house, will be located the control for the valves. This may take any form that convenience or engineering may dictate for rotating the valves. 50 As shown in the drawings, an upright 35 is provided with a segmental gear 36 journaled therein with a second segmental gear 37 in mesh with the gear 36. The gear 36 carries a walking beam 38 from the opposite ends of 55 which extend cables 39 and 40 passing about a direction changing mechanism, as a pulley 41, and over the first of the pulleys 32. Any means for applying manual stress for 60 actuating the gears 36 and 37 may be provided and is here indicated as a crank arm 42.

In operation the several tanks 13 will be filled with water or other liquid for ballast purposes. When through any contingencies of operation it becomes necessary or desirable to discharge a part of said ballast for the 70 purpose of lightening the ship, the crank arm 42 may be moved to the dotted line position 42', whereupon the several valves 23 will be rotated in the direction indicated by the arrow at Figure 4 to bring the opening 75 26 into such position as to drain out a predetermined part of the ballast through the pipe 25 as hereinbefore more fully disclosed, and simultaneously, if the power plant is in operation, it is desirable to divert the exhaust to the conduit 16, whereupon the ballast will be discharged from the spray head 17 in the form of a mist and will not have any discommoding effecting upon persons or property situated below.

When through the same or other contingencies of operation it is necessary or desirable to discharge all of the ballast, a further movement of the crank arm 42 in the same direction, will bring the opening 29 into registry with the pipe 28 and the content of the containers 13 will be discharged in the manner hereinbefore described.

While in the drawings simultaneous control of all of the several tanks has been shown, it is obvious that such control of all the tanks is immaterial to the present invention and that certain containers of the several tanks may be selected to which such device is applied, other being provided with no discharge means or with such other type of discharge means as may be selected or with separate installations of the present type of discharging apparatus for the control of separate units or groups of units as may be found feasible.

Of course, the aircraft ballast apparatus herein illustrated, may be modified in various ways without departing from the invention herein set forth and hereinafter claimed.

The invention is hereby claimed as follows:—

1. An aircraft ballasting apparatus comprising a plurality of ballast containers, a conduit common to said containers, a valved passage from said containers to said conduit, and manual means for simultaneously controlling said valves.

2. An aircraft ballasting apparatus comprising a plurality of ballast containers, a conduit, branch conduits forming communication between said conduit and said containers, valves interposed in said branch conduits, and means including said branch conduits and valves for discharging a pre-determined portion of the ballast content from 125 said containers.

3. An aircraft ballasting apparatus comprising a plurality of ballast containers, a conduit, a spray head mounted upon said conduit, branch conduits extending from said 130

conduit to the said containers, valves controlling the passage through said branch conduits, a power plant, and a by-pass from said power plant to said conduit.

4. An aircraft ballasting apparatus comprising a craft body, a plurality of containers mounted in said body, a conduit mounted in said body beneath said containers, laterals leading from said conduit to said containers, valves in said laterals, and manual means for operating said valves.

5. An aircraft ballasting apparatus comprising a craft body, a plurality of ballast containers carried by the body, a conduit within the body and beneath the containers, 15 a spray head terminating said conduit without the body, laterals leading from said containers to said conduit, valves controlling the flow of ballast through said laterals, and means to apply manual stress to operate said 20 valve simultaneously.

6. An aircraft ballasting apparatus comprising a plurality of ballast containers, a conduit beneath said containers, laterals connecting said conduit with each of said containers, a valve controlling the flow of ballast through each of said laterals, means to manually move said valve to discharge a pre-determined portion of the ballast through one 30 of said laterals and into the conduit, and means to move the valve a further distance to discharge the remaining portion of said ballast into said conduit.

7. An aircraft ballasting apparatus comprising a ballast container, a conduit located beneath the ballast container, laterals leading from said conduit to said container, one of said laterals extending a pre-determined distance into said container and one stopping short of said first mentioned distance, and a 40 valve controlling both of said laterals independently.

8. An aircraft ballasting apparatus comprising a ballast container, a conduit adjacent the container, laterals extending from said conduit, one terminating at the interior surface of said container and one extending a pre-determined distance across said container, and a valve interposed in both of said laterals controlling the flow electively through either of said laterals to said conduit.

In testimony whereof I have signed my name to this specification.

MAX B. PUPP.
